United States Patent Office

Des. 190,902
Patented July 18, 1961

190,902

DRUG CART

Frederic T. C. Brewer, '19—11 Valley Road,
Drexel Hill, Pa.

Filed Feb. 17, 1961, Ser. No. 63,977

Term of patent 14 years

(Cl. D14—3)

FIG. 1.

Des. 190,902

PAGE 2

FIG. 2.

FIG. 3.

FIG. 1 is a perspective view of a drug cart, showing my new design;

FIG. 2 is a perspective view showing the bottom, rear and side opposite that shown in FIG. 1;

FIG. 3 is a perspective view of a modified form of the cart shown in FIG. 1, the rear and opposite side being substantially plain.

I claim:

The ornamental design for a drug cart, as shown and described.
